Primary Examiner — Paula Allen Greene*(74) Attorney, Agent, or Firm* — Li & Cai Intellectual Property (USA) Office**CLAIM**

The ornamental design for a “wireless headset,” as shown and described.

DESCRIPTION

FIG. 1 is a perspective view of a wireless headset showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
